DRESSING DEVICE FOR GRINDING WHEELS

Gilbert Stewart, Detroit, Mich., assignor to Ex-
Cell-O Corporation, Detroit, Mich., a corpora-
tion of Michigan

Application October 17, 1940, Serial No. 361,608

14 Claims. (CL 125—11)

The invention relates to dressing devices for grinding wheels and the general aim of the invention is to provide a device of this character having improved efficiency and accuracy in operation.

An object of the invention is to provide a dressing device embodying new and improved means for adjusting the device according to the requirements of the wheel to be dressed.

Another object is to provide a new and improved means for supporting a plurality of dressing tools for movement relative to each other and to the grinding wheel.

Another object is to provide novel means for effecting the movements of the wheel dressing means relative to the grinding wheel through a cycle in which the dressing means is advanced toward the wheel, is moved to dress the wheel, is retracted or withdrawn from the wheel and is returned to an initial or starting position.

Other objects and advantages will become apparent in the following description and from the accompanying drawings in which:

Fig. 1 is a perspective view of a dressing device embodying the features of the invention.

Fig. 2 is a front view of the device as seen from the position of the grinding wheel.

Fig. 3 is a plan view of the device, omitting the supporting structure for the cradle.

Fig. 4 is a longitudinal sectional view on a vertical plane taken substantially along the line 4—4 of Fig. 3.

Fig. 5 is a transverse sectional view on a vertical plane taken along the line 5—5 of Fig. 4.

Fig. 6 is a sectional view on a vertical plane showing details of a dressing tool supporting means and is taken along the line 6—6 of Fig. 3.

Figs. 7 and 8 are diagrammatic views illustrating various relationships of the dressing tools and the grinding wheel.

While the invention is susceptible of various modifications and alternative constructions, I have shown in the drawings and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

Dressing devices embodying the features of the invention are adapted for association with various types of grinding machines such for example as that shown and described in the copending

application of Max A. Mathys Serial No. 350,348 filed August 3, 1940. The machine disclosed in said application is adapted for thread grinding operations and in the present application the dressing device has been illustrated and will be described as being arranged to dress a grinding wheel to a thread grinding peripheral contour.

The exemplary device, as may be seen from Fig. 1, embodies an arrangement of several superimposed supporting means and slides including a dresser slide 10 for supporting the entire dressing device in operative relation to the grinding wheel 11, a dresser base 12 which is adjustable to obtain the required setting of the device for different forms of threads, a cradle member or support 13 for adjusting the dressing device to the helix angle of the grinding wheel, an approach slide 14 arranged for reciprocatory movement to carry the dressing tools into and away from an operative relation to the grinding wheel, and an actuating slide 15 movable to traverse the dressing tools carried by the approach slide across the grinding wheel surface to be dressed.

Referring more specifically to the structural relationships, the dresser slide is supported in any suitable manner for set-up adjustments as by a grinding wheel slide 16 forming a part of the machine structure of the Mathys application above identified. As shown in Fig. 4, the plane upper surface of the dresser slide 10 supports a plate 17 constituting the dresser base 12. Preferably, the dresser base 12 is mounted on the dresser slide 10 for relative pivotal adjustment to enable the dressed mechanism to be properly set to dress a grinding wheel which may be arranged to make cylindrical or tapered cuts. Thus, the dresser slide carries a pivot pin 18 engaged by the dresser base 12 and such means as spaced clamping plates 19 secured by bolts 20 maintain the desired angular relationship of a dresser base to a dresser slide. The pivot 18 is located at the forward end of the dresser slide and the vertical axis thereof extends through a point about which certain of the dresser tools are adjustable. This point will be hereinafter more particularly referred to.

At the front and rear ends of the dresser base are upstanding flanges 21 and 22, respectively, having upwardly facing concave ways 23 therein to support the cradle member 13. This member is a frame having arcuate front and rear guides 24, 25 complementary to the ways 23 connected by side and intermediate cross bars 26, 27 (Fig. 5). The rear guide 25, and its asso-

ciated way 23, preferably have an undercut interfitting relation, indicated at 28, defining the rearward position of the cradle. The position of angular adjustment of the cradle to the dresser base may be suitably fixed by such means as clamping members 29, 30 secured as by bolts 31 to the front of the dresser base 12 for binding engagement with the front face of the front guide 24. By this adjustment the operator sets the dressing device according to the helix angle of the grinding wheel and the angularity of the adjustment may be suitably indicated by a scale 32 on the front face of guide 24, the edge 33 of the clamp 29 being used as an indicator.

The intermediate cross bar 27 is, as may be seen in Fig. 5, of substantial width and has a wide longitudinally extending recess 34 therein. At each side of the recess a rail 35 is secured as by screws 36 and the inner face of each rail has a longitudinally extending groove 37.

The approach slide 14 is mounted above the intermediate cross bar 27 and includes, for convenience of manufacture and assembly, lower and upper sections 38, 39, respectively secured together as by screws 40. The lower section 38 extends between the rails 35 and the side faces thereof have longitudinally extending grooves 41 opposing the grooves 37 in the rails. Interposed between each pair of grooves 37, 41, which constitute raceways, is a series of anti-friction roller elements 42 held in place by a spacer or retainer plate 43 to complete the bearing relationship. One of the rails, for example, the left hand rail 35, may be laterally adjusted, as by set screws 44, to determine the desired operating relation of the rails, approach slide and bearings in which the frictional resistance to movement of the approach slide relative to the cross bar 27 is at an approximate minimum.

At its rear end the upper section 39 of the approach slide has an upstanding part 45 (Figs. 4 and 5) provided on its upper surface with longitudinally extending undercut or dovetail ways 46 to receive the actuating slide 15. One surface on the actuating slide that engages one of the undercut ways 46 is defined by a bar 47 in the nature of a gib which is resiliently urged toward the associated ways 46 by such means as springs 48 backed by tension adjusting screws 49. The purpose of this arrangement is to enable the frictional resistance to movement of the actuating slide 15 relative to the approach slide 14 to be adjusted to a point where it is greater than the frictional resistance between the approach slide and the intermediate cross bar 27.

At the rear end of the approach slide is an upstanding bracket 50 supporting a housing 51 for the driving mechanism. This mechanism includes a shaft 52 rotatably mounted in the housing 51 to extend into a longitudinal bore 53 located centrally of the actuated slide. Rigidly seated in the front end of the bore 53 is a tubular nut 54 engaged by a feed screw 55 on the end of the shaft 52. Within the housing 51 the shaft 52 has a worm wheel 56 secured thereto and engaged by a worm 57 on a drive shaft 58 suitably journaled in the housing. In the present instance power is delivered to the drive shaft 58 from a motor (not shown) through a flexible drive cable indicated at 59 in Figs. 1 and 2. A reversible motor is employed for driving the actuating slide in opposite directions.

Through the relationship of the frictional resistances to movement of the approach and ac-

tuating slides, the cycle of operating movements may be obtained in a simple manner by the single feed screw 55. Thus, the initial movement resulting from actuation of the feed screw is a joint travel of the approach and actuating slides as a unit since the substantially heavy friction between the actuating slide and the approach slide prevents relative movement of these parts as long as the approach slide is free to move. The permissible movement of the approach slide is relatively short and may be limited in any suitable manner as by pin 60 on the intermediate cross bar engaging a somewhat elongated aperture 61 in the lower section 38 of the approach slide.

As soon as the approach slide is moved in either direction to a limit of its movement, continued rotation of the feed screw 55 will move the actuating slide relative to the approach slide. Hence, considering that the slides are in their retracted or rearward positions, initial rotation of the feed screw 55 will first move the approach slide to its forward limit as shown in Fig. 4, and thereafter continue the forward movement of the actuating slide. Reverse rotation of the feed screw will first move the approach and actuating slides rearwardly to the limit of movement of the approach slide, and thereafter continue the rearward movement of the actuating slide. These movements, in the order in which they occur, are utilized first to shift the dressing tools into an operative relation with respect to the grinding wheel, then to effect a dressing movement of the dressing tools across the surfaces to be dressed, then to retract the tools from the grinding wheel and finally to return the dressing tools to their initial position.

In the present embodiment, three dressing tools and individually adjustable supporting assemblies therefor are provided comprising, as may be seen in Fig. 3, two opposed assemblies 62, 63 for dressing the opposite side faces 64, 65 of a peripheral portion of the grinding wheel 11 and an intermediate assembly 66 for dressing the peripheral face or edge 67 of the wheel. Each dressing tool assembly includes means for pivotally supporting the tool for swinging movement relative to the surface of the wheel to be dressed by that tool.

Referring first to the structure of the intermediate dressing tool assembly 66, a base block 68, Figs. 3 and 4, is mounted on the upper section 39 of the approach slide for pivotal movement about a pin 69 carried by the approach slide. This pivotal movement is to enable proper setting up of the intermediate dressing tool in the device, and the position of the block 68 may be determined and fixed in any suitable way as by opposed set screws 69a on the block for engagement with a pin 70 carried by the approach slide and extending into a transversely extending slot 71 on the block. Clamping screws 72 or the like rigidly secure the block to the approach slide in any position of adjustment. The block has a longitudinally extending bore 73 supporting a pivot member 74 in a position fixed by a set screw 75.

A supporting member 76 for the dressing tool 70 is in the nature of a swinging bracket having a bifurcated lower end portion providing spaced arms 77 dimensioned to straddle the opposite ends of the pivot member 74. Pivot bearings 78 are seated in opposed recesses provided in the end faces of the pivot member 74, in one of the

arms 71 and in a plug 78 carried by the other arm. Spacers 80, or the like, may be interposed between the pivot member 74 and the arms 71 to protect the pivot bearings. In the present instance, these bearings consist of anti-friction balls. The supporting member near its front end has an upstanding part 81 which is bored near its upper end, as at 82, to receive the supporting sleeve 83 in which the dressing tool 84 or diamond holder, is mounted. The axial position of adjustment of the sleeve 83 (and consequently of the diamond) may be suitably determined by a micrometer device 85, the diamond holder 84 being fixed by such means as a back-up screw 86 and a set screw 87.

Toward its rear side, the supporting member 78 carries a rounded head 88 for engagement with a slot 89 formed in a driving cam 90. The slot, as shown in Fig. 3, is at an angle to the pivotal axis about which the supporting member 76 swings, so that longitudinal movement of the cam will swing the supporting member transversely. The driving cam extends over and is secured to the upper surface of the actuating slide 15 by such means as a clamping screw 91 extending through a longitudinally elongated slot 92 to engage the actuating slide. This arrangement enables adjustment of the driving cam relative to the head 88 engaged thereby, to determine the initial position of the intermediate dressing tool.

The oppositely disposed dressing tool assemblies 62, 63 are substantially alike and it will, therefore, be necessary to describe the structure of but one assembly. Thus, referring to Figs. 2, 3 and 6, the dressing tool assembly 63 includes a supporting base 93 which may be formed as an integral upwardly projecting part of the upper section 39 of the approach slide. The upper surface of the base is arcuately traversed by a T-slot 94 and the slots on both bases are formed on radii of equal lengths about a common center point A located within and in close proximity to the perimeter of the grinding wheel and substantially on the center plane thereof. Each slot 94 is, as shown in Fig. 6, engaged by spaced keys 95 secured to the opposite sides of a block 96. Clamping means 97 on the block 96 engages the T-slot to secure the block in any desired position of arcuate adjustment relative to the base. The keys 95 guide the movement of the block along the slot 94 to various adjusted positions and accurately maintain the proper relation between the block 96 and the base 93.

The block 96 carries a pivot member 98 disposed on an axis which intersects the vertical line through the point A and the construction of the pivot member 98 and its association with a swinging dressing tool supporting member 99 need not be more particularly described since it is substantially the same as that of the intermediate dressing tool assembly. At the side of the supporting member 98 nearest the wheel a vertical bore 100 is formed to receive a depending pin 101 on a tool head 102 in which a dressing tool 103 is mounted. A clamping screw 104, or the like, acts with a backing screw 105 to maintain the dressing tool 103 in position for proper operative engagement with the wheel. The diamond tools are arranged at an angle toward the periphery of the grinding wheel. Therefore, by rotating the diamond tool 103, after it has become worn, and locking it in a new position by means of the screw 104, a sharp edge or corner may again be presented to the

wheel. A set screw 104 engages the pin 101, and permits pivotal adjustment of the tool head 102 so as to change the position and the angular contact of the diamond relative to the grinding wheel.

On the upper surface of the support 99 is a rounded head 106 forming part of a ball and socket joint 107 (Fig. 3) by which the swinging support 99 is connected with an actuating rod 108. The pull rod extends rearwardly to a position above the actuating slide 15 and at its rear end has a ball and socket connection 109 with a slide nut member 110 adjustable along the length of a longitudinally extending T-slot 111.

15 The opposed dressing tools 103 of the assemblies 62, 63, may be conveniently adjusted along their associated arcuate grooves 94 to determine the plane of movement of the dressing tools 103 relative to the grinding wheel, these planes being determined by the angles to which the surfaces 64, 65 on the grinding wheel are to be dressed. The positions of adjustment may be designated by scales 112 or the like on the bases 93 and cooperating indicators 113 on the blocks 96. By adjusting the connections between the actuating rods 108 and the actuating slide 15 a proper driving connection between the actuating slide and both dresser tool assemblies 62, 63 may be readily obtained in all positions of adjustment of these assemblies.

As may be seen in Fig. 2, the three dresser tools are so arranged that one tool will not interfere with either of the other tools in the swinging movement thereof. Thus, the tools are arranged at different vertical levels, the intermediate tool in this instance being at the higher level and the tool head 102 on the right hand assembly 62 being somewhat longer in a vertical direction than the corresponding head on the assembly 63. The assembly 62 is therefore disposed above the tool on the assembly 63 and below the tool on the intermediate assembly. It should be mentioned that the pivotal axis about which the dressing tool on the intermediate assembly swings, will normally also intersect a vertical line through the point A and that the axis of the pivot pin 101 about which the dresser base is adjustable with respect to the dresser slide also coincides with this line.

40 In setting up the machine for operation, the dresser base will be adjusted with respect to the dresser slide according to the form of the thread which is to be ground by the grinding wheel. The cradle is positioning according to the helix angle to which the grinding wheel is set. For example, in Fig. 2 the cradle is adjusted to position the tools for dressing a wheel set at a helix angle of 5°. Each of the dressing tool assemblies is individually adjusted so that each tool will describe a desired path across a surface of the grinding wheel and the several driving connections of the assemblies with the actuating slide are adjusted to locate the initial or starting position of each tool. Thus, the dressing tool on the intermediate assembly 63 is adjusted to a position in which the diamond will be located initially at one side of the end face 67 (see Fig. 3) for swinging movement on a plane parallel to the desired plane of that face. The opposed assemblies 62, 63 are adjusted along the slots 94 to positions in which the pivotal axis of each assembly is perpendicular to the desired plane of the associated side face 64 or 65. The actuating rods 108 are adjusted with respect to the actuating slide so that the assemblies 62, 63

will move from an initial position radially outwardly of the end face 61 of the grinding wheel inwardly across the side faces 64, 65. The initial adjustments of the dressing tools are determined with respect to the advanced or forward limit of the approach slide so that in operation the diamonds will be moved by the forward travel of the approach slide into the planes to which the wheel surfaces are to be dressed.

In performing the dressing operation a circuit to the motor which drives the feed screw 55 is established to turn the feed screw in a direction that will move the actuating slide forwardly. Because of the greater friction between the actuating slide and the approach slide than between the approach slide and the dresser base, the approach and actuating slides will move as a unit until the actuating slide reaches its forward limit of travel. At this point, as shown in Fig. 3, the several diamonds are each disposed on the plane to which the grinding wheel surfaces are to be dressed. Continued movement of the actuating slide (which movement is relative to the approach slide) will swing each of the dresser assemblies 62, 63, 66 in a direction that will carry the diamonds across the corresponding surfaces of the grinding wheel to dress the wheel. This movement of the diamonds relative to the wheel is illustrated in Fig. 7. It may be noted that the extent of swinging movement of each of the dresser tools is immaterial as long as each tool is caused to traverse its corresponding surface.

When the dressing operation is complete, the driving motor is reversed to retract the actuating slide. Again, because of the frictional differences imposed by the bearing surfaces of the actuating slide and approach slide, the two slides will be retracted as a unit, thereby initially moving the dressing tools away from the grinding wheel as indicated in full outline in Fig. 8. When the approach slide reaches its rear limit of movement, the continued travel of the actuating slide will return the tools to their initial positions. It will be evident, therefore, that by the present construction a single driving means having individually adjustable connections with each of the dressing tools, moves the tools through all of their movements relative to the grinding wheel.

The reversal of the motor for driving the feed screw may be automatic. Thus, as shown in Fig. 3, a switch, not shown but located in the housing 114 on the actuating slide, has a contact controlling operator 115 extending therefrom. In the path of travel of the operator 115 and on the opposite sides thereof, are pins 116 and 117 adjustably carried by a bracket 118. The circuit arrangement is such that when the grinding wheel is to be dressed, a circuit to the driving motor is closed either automatically or by the operator of the machine. The circuit thus established drives the motor in a direction to move the actuating slide forwardly, which movement continues until the operator 115 strikes pin 116 to establish a reverse circuit and break a holding circuit which has maintained the circuit first established. The return or retracting movement of the actuating slide continues until the operator 115 strikes pin 117 to break the last established or reversing circuit.

It will be evident from the foregoing that a novel dressing device has been provided in which each of the dressing tools is individually adjustable to dress a grinding wheel to a required contour. The several dressing tools are actuated in

5 also serves as the means for effecting the approach and retracting movements of the dressing tools relative to the grinding wheel. The dressing mechanism may be readily adjusted to dress grinding wheels set for different helix angles or forms of threads.

I claim as my invention:

1. A dressing device for grinding wheels having, in combination, a support, a base mounted on said support for adjustment about a vertical axis, an arcuate cradle carried by said base for adjustment according to the helix angle of the grinding wheel to be dressed, a first slide carried by said cradle for reciprocatory movement toward and away from the grinding wheel, a plurality of dressing tools, means individually supporting each of said dressing tools for adjustment on said slide relative to each other and to the grinding wheel and including pivot means permitting swinging movement of said dressing tools across a surface to be dressed, a second reciprocatory slide mounted on said first slide, individual driving connections between said second slide and each of the dressing tool supporting means, means for driving said second slide through a reciprocatory stroke, means for imposing a greater frictional resistance to movement between said first and second slides than between said first slide and said cradle, and means for limiting the extent of movement of said first slide.

2. A dressing device for grinding wheels having, in combination, a base, a frame carried by said base for adjustment to the helix angle of the grinding wheel to be dressed, a first slide carried by said frame for reciprocatory movement toward and away from the grinding wheel, a plurality of dressing tools, means individually supporting each of said dressing tools for adjustment on said slide relative to each other and to the grinding wheel and including pivot means permitting swinging movement of said dressing tools across a surface to be dressed, a second slide mounted on said first slide, individual driving connections between said second slide and each of the dressing tool supporting means, means for advancing and retracting said second slide, means for imposing a greater frictional resistance to movement between said first and second slides than between said first slide and said frame, and means for limiting the extent of movement of said first slide.

3. A dressing device for grinding wheels having, in combination, a support, a frame carried by said support for adjustment to the helix angle of the grinding wheel to be dressed, a first slide carried by said frame for reciprocatory movement toward and away from the grinding wheel, a plurality of dressing tools, means supporting each of said dressing tools for swinging movement across a surface to be dressed, means for adjusting an opposed pair of said supporting means about a common center, a second slide mounted on said first slide, individual driving connections between said second slide and each of the dressing tool supporting means, means for driving said second slide through a reciprocatory stroke, means for limiting the extent of movement of said first slide, and means for effecting movement of said first slide to a limit prior to independent movement of said second slide relative thereto.

4. A dressing device for grinding wheels having, in combination, a support, a reciprocator slide on said support, a plurality of dressing tool

individually supported on said slide for relative swinging movement on different planes, means for adjusting said dressing tools for swinging movement in different angular planes, a second slide mounted on the first mentioned slide, individual driving connections between said second slide and each of the dressing tools for swinging said dressing tools, and driving means for reciprocating said first slide and for moving said second slide to swing said dressing tools.

5. A dressing device for grinding wheels having, in combination, a support, a slide on said support movable toward and away from the grinding wheel, a plurality of dressing tools supported for swinging movement across surfaces to be dressed, means for adjusting said tools to different angular planes of movement, a second slide, driving connections between said second slide and each of the dressing tools adjustable in accordance with the different positions of said tools, and means for moving said slides.

6. A dressing device for grinding wheels having, in combination, a support, a slide on said support movable toward and away from the grinding wheel, a plurality of dressing tools supported for swinging movement across a surface to be dressed, a second slide mounted on said first mentioned slide, driving connections between said second slide and said dressing tools, means for driving said second slide movable in the same direction as said first slide, means for limiting the extent of movement of said first slide, and means for imposing a greater frictional resistance to movement between said first and second slides than between said first slide and said support.

7. In a dressing device for a grinding wheel, the combination of a support arranged to be located adjacent the grinding wheel to be dressed, a pair of spaced members mounted on said support and disposed one on either side of the grinding wheel, means for adjusting each of said members along an arcuate path about a common center, dressing tools mounted on said members for pivotal movement relative thereto about axes substantially perpendicular to the planes of the surfaces to be dressed by said tools on the grinding wheel, and common driving means individually and adjustably connected with each of said dressing tools.

8. In a dressing device for a grinding wheel, the combination of a support, a pair of spaced members mounted on said support and disposed one on either side of the grinding wheel, means for adjusting each of said members along an arcuate path about a common center, a dressing tool supported on each member for pivotal movement to traverse the tool across a corresponding surface of the grinding wheel, a third dressing tool pivotally mounted on said support intermediate said first mentioned dressing tools for swinging movement on an axis paralleling the plane of the grinding wheel, and common driving means individually and adjustably connected with said dressing tools.

9. In a dressing device for a grinding wheel, the combination of a support arranged to be located adjacent the grinding wheel to be dressed, a pair of spaced members mounted on said support and disposed one on either side of the grinding wheel, means for adjusting each of said members along an arcuate path about a common center, a dressing tool supported on each member for pivotal movement relative thereto, a third dressing tool mounted between said dressing tools on said members for movement transversely of the plane of the grinding wheel, said dressing tools

being disposed in spaced relation out of contact with each other during the movement thereof, and a common driving means individually and adjustably connected with said dressing tools.

5 10. In a dressing device for a grinding wheel the combination of a plurality of dressing tools, means for supporting each of said dressing tools for swinging movement on a plane parallel to the plane of a surface to be dressed, means for individually changing the plane of movement of each tool, a base on which the supporting means is mounted for movement toward and away from the grinding wheel to carry the tools into and out of positions in which their planes of movement coincide with the planes to which the surfaces on the grinding wheel are to be dressed, and driving means for effecting such movement of the supporting means and for swinging said tools through dressing and return strokes.

20 11. In a dressing device for a grinding wheel the combination of a plurality of dressing tools, means for supporting each of said dressing tools for swinging movement on a plane parallel to the plane of a surface to be dressed, means for individually changing the plane of movement of each tool, a base on which the supporting means is mounted for movement toward and away from the grinding wheel to carry the tools into and out of positions in which their planes of movement coincide with the planes to which the surfaces on the grinding wheel are to be dressed, and driving means for said supporting means and said dressing tools operable to advance the supporting means toward the grinding wheel, swing the dressing tools through dressing strokes, retract the supporting means, and return the dressing tools to their initial positions in that order.

30 12. In a dressing device for a grinding wheel the combination of a plurality of dressing tools, means for supporting each of said dressing tools for movement on a plane parallel to the plane of a surface to be dressed, means for moving the supporting means as a unit toward and away from the grinding wheel to carry the tools into and out of positions in which their planes of movement coincide with the planes to which the surfaces on the grinding wheel are to be dressed, and a single driving means for consecutively moving the supporting means toward the grinding wheel, moving said tools across the surfaces to be dressed, retracting the supporting means and returning the tools to the starting position thereof.

35 13. A dressing device for grinding wheels having, in combination, a support, a pair of superimposed slides mounted on said support for reciprocatory movement relative to said support and to each other toward and away from the grinding wheel, a plurality of dressing tools supported on one of said slides for swinging movement across a grinding wheel surface to be dressed, individual driving connections between the other of said slides and each of said dressing tools for effecting swinging movement thereof, and a single driving means for moving said slides together to shift said dressing tools into operative relation to the grinding wheel and for thereafter independently continuing the movement of the slide that is drivingly connected with the dressing tools.

40 14. A dressing device for grinding wheels having, in combination, a support, a pair of superimposed slides mounted on said support for reciprocatory movement relative to said support

and to each other toward and away from the grinding wheel, a plurality of dressing tools supported on one of said slides for swinging movement across a grinding wheel surface to be dressed, individual driving connections between the other of said slides and each of said dressing tools for effecting the swinging movement thereof, and a single driving means for shifting said slides as a unit toward and away from a position in which said dressing tools are disposed for operative engagement with the grinding

wheel and for thereafter independently continuing the movement of the slide that is drivingly connected with said dressing tools to swing said dressing tools through dressing and return strokes, and means for so correlating the movements of the slides that their movement as a unit toward or away from the grinding wheel precedes the independent movement of the slide that is drivingly connected with the dressing tools.

GILBERT STEWART.
